THERMOSTAT CONTROL FOR GAS
BURNERS

John R. MacGregor, Albany, Leon T. Folsom,
Berkeley, and Samuel H. Edwards, Richmond,
Calif., assignors to Standard Oil Company of
California, San Francisco, Calif., a corporation
of Delaware

Application November 4, 1933, Serial No. 696,648

2 Claims. (Cl. 236—1)

This invention relates to a temperature responsive control for a gas burner, and particularly to one which forms a part of a portable heater such as is used to keep the temperature in a compartment, such as a refrigerator car carrying perishable food products, from becoming too low. In severe winter weather, when temperatures of 10-40 degrees below zero, Fahrenheit, are sometimes encountered, it becomes necessary to protect perishable foodstuffs, such as apples, from exposure to temperatures below 32 degrees F. while they are being transported. This may conveniently be done by a portable heater consisting of a small tank of liquefied petroleum gas such as propane, which is burned in a suitably controlled gas burner. This invention relates particularly to a temperature responsive control device for such a burner.

The service requirements for such a control mechanism are unusually severe, as it must be accurate enough to hold the air temperature in a car within a range of a few degrees at about 32° F., and yet not be damaged or lose its adjustment from the jarring, shocks and general rough treatment that it receives while travelling, practically unattended, in a refrigerator car for a period of five to fifteen days. There must also be provision for safety under all conditions, such as an accidental extinguishing of the gas burner flame, so that the car will not become filled with an inflammable or explosive gas-air mixture, with possible disastrous results. Another feature that has sometimes been overlooked is the requirement that the calibration shall remain constant for changes in atmospheric pressure, so that changes in elevation of 6000 to 8000 feet, while passing from sea level over high mountain passes, will not affect the operation. Temperature responsive devices which balance the vapor tension of a volatile liquid in a suitable flexible walled bulb against atmospheric pressure would have this objectionable lack of calibration stability. This is avoided in this example by the use of bimetallic thermostat elements.

A suitable portable heater structure in which this invention may be used is disclosed and claimed in a copending application of Carl C. Claesson, Serial No. 666,558, filed April 17, 1933, which matured into Patent No. 1,987,603 on January 15, 1935. This consists generally of a casting or stack, in which a suitable burner is mounted, and to which a standard cylindrical tank of liquefied petroleum gas, such as propane, may be secured while the device is to be used. A desirable form of burner is that shown and claimed

in a copending application of John R. MacGregor, Serial No. 691,904 filed October 3, 1933, which matured into Patent No. 2,001,739 on May 21, 1935. This burner is adapted to burn equally well with a high or a low flame, thus requiring no separate pilot burner or other ignition means, and is particularly adapted to be controlled by a device such as that to be described below.

It is an object of this invention to provide a compact and simple temperature responsive control device for a single gas burner, which will increase or decrease the gas flow as required by changing temperature conditions.

Another object is to provide a gas burner control device which will automatically and positively shut off all the gas to the burner when the flame becomes extinguished from any cause.

Another object is to provide a gas burner control means which will be sensitive to a temperature change of two or three degrees Fahrenheit, which will be adjustable in setting, and which may be operated by unskilled attendants.

Another object is to provide a gas burner control device which forms a compact and simple unit with the burner to be controlled, and which may be easily and simply operated and adjusted.

These and other objects and advantages of this invention will be more fully apparent from the following detailed description of a preferred embodiment, and from the accompanying drawings, which supplement the description and form a part of this specification.

In the drawings:

Figure 1 is a vertical part sectional elevation of a burner assembly involving a preferred embodiment of this invention and showing the relation between the temperature controller, burner and safety shut-off means.

Figure 2 is an end elevation of the burner and control mechanism shown in Figure 1.

Figure 3 is a plan of the burner and control mechanism shown in Figure 1, and illustrates the burner safety shut-off thermostat and lever in its cold or actuated position.

Figure 4 is a horizontal sectional view through the valve body on the line IV—IV of Figure 2, and illustrates the temperature control and safety shut-off valves.

Figure 5 is a horizontal sectional view on the broken line V—V of Figure 2 and illustrates the temperature control thermostat.

Figure 6 is a sectional view of the spiral bimetallic thermostat element used for temperature control, on line VI—VI of Figure 5.

Referring to the drawings and particularly

to Figures 1 and 4, the numeral 11 represents a valve body, which may preferably be a casting provided with two side plates 12 and 13 which cooperate with recesses in body 11 to form a gas inlet chamber 14 and a valve chamber 15. Plate 12 is made with a threaded opening 16 into which a suitable gas supply pipe (not shown) may be screwed. Both plates are secured to body 11 by bolts 17 and nuts 18 and are made gas tight by gaskets 19.

The burner structure generally designated 20 is mounted on the top of valve body 11 by screws 21. The exact construction of the burner is not important, but one which will give a stable flame 15 at a gas rate of as low as 0.1 cu. ft. per hour from liquefied petroleum gas such as propane, and yet properly burn as high as 15 cu. ft. of such gas per hour, is desirable. This type of burner acts as its own pilot, and avoids the complication and 20 expense of a double unit of main and pilot burners.

The safety shut-off thermostat element 22 may conveniently be mounted within the tube of the burner, adjacent its outer end, as shown in Figures 1 and 3. The thermostat element 22 is of the usual bimetal and is so exposed to heat from the flame that the low pilot flame which burns when the ambient temperature is above the desired minimum will cause it to remain in its expanded or latched position, while the higher heat from the burner when full gas flow is admitted will not cause permanent deformation and change in calibration. Thermostat element 22 in this example is bent to approximately a circle or 30 hoop, with one end fixed to the burner tube 20, by a screw 23, and the other end free to move outwardly when its temperature is increased. Figures 1 and 3 show the thermostat element 22 in its cold or released position.

40 Safety shut-off thermostat element 22 is provided with a hole 24 near its outer or free end, into which the outer end 25 of the shut-off valve stem 26 is adapted to pass when the temperature of 22 is low due to an absence of flame in the burner 20. Valve stem 26 is preferably bent as shown at 27 to form a convenient handle for holding the safety shut-off valve, to be described below, in its open position during the lighting of the burner 20. A spring 28 is secured to the body 50 of burner 20 and also to valve stem 26 to urge the latter in a counter-clockwise direction, so that it will tend to rotate its upper end 25 to enter hole 24 in the thermostat element 22 if the element moves to its cold or contacted position 55 shown in Figure 3.

The lower end of safety shut-off valve stem 26 extends through a hole 29 in the base of burner 20 into a corresponding hole 30 in valve body 11 which opens into the gas inlet chamber 14 (Figures 1 and 4). A resilient grommet 31, the flange of which is clamped between the burner base plate and a recess 32 in valve body 11, and which fits tightly about the valve stem 26, prevents gas leakage to the atmosphere from gas inlet chamber 14. The slight rotation of the stem 26 in moving the valve on its lower end from open to closed position is readily taken up by torsion in the body of grommet 31.

The partition or wall in valve body 11 which 70 separates the gas inlet chamber 14 from the valve chamber 15 is drilled with a small passage 33 as shown in Figures 1 and 4, and the inlet end of the passage is provided with a nozzle or valve jet 34. A valve arm 35 is secured to the lower end 75 of the stem 26 as by a set screw 36, and carries a

small resilient valve disc 37 which may be of rubber. This disc 37 is adapted to seat upon and close the valve jet 34 when the safety shut-off thermostat element 22 is cold and allows the end 25 of the valve stem 26 to enter the hole 24, as 5 shown in Figure 3. Thus, when the burner is cold or is without a flame, the gas passage 33 between the gas inlet chamber 14 and the valve chamber 15 is positively closed.

A second passage 38 leads from valve chamber 10 15 into the center partition of valve body 11 (Figure 4) and is also provided with a nozzle or valve jet 39. A continuation 84 of passage 38 leads upwardly through the center of the valve body 11 and is threaded at its upper end to receive a burner nozzle 40 (Figure 1). Passage 84 is preferably fairly large to provide a gas volume to prevent collapse of the flame when valve 39 is shut suddenly. Burner body 20 is suitably drilled as at 15 41 to allow the nozzle 40 to project upwardly as 20 shown. Air for combustion in the burner 20 may be inspirated through a plurality of holes 42.

A temperature control valve stem 43 is fitted at its upper end with a valve arm 44, set screw 45 and a resilient valve disc 46, which latter is 25 adapted to seat upon nozzle or valve jet 39 and thus shut off the gas passage 38 to burner nozzle 40. Valve stem 43 passes downwardly through a hole 47, sealed by a resilient grommet 48 and then engages a temperature control thermostat 30 mechanism generally designated 49 through the medium of the offset or crank section 50. The lower end of valve stem 43 is preferably received and supported by a bearing such as the ball bearing cup 51, which may be suitably supported on 35 the bottom plate of the thermostat mechanism.

Thus, when the ambient temperature in the compartment in which the heater is placed falls below the predetermined minimum to which thermostat 49 is adjusted, the crank section 50 40 will be moved by thermostat 49 to cause a clockwise rotation of valve stem 43 (Figure 4) to open the valve jet 39 and allow gas to pass from valve chamber 15 into burner nozzle 40, provided, however, that the safety shut-off valve nozzle 34 has 45 previously been opened as explained above.

In order to provide a small flow of gas from valve chamber 15 to burner nozzle 40 when the ambient temperature is above the predetermined minimum and valve nozzle 39 is closed, so that a 50 low or pilot flame will burn at the top of burner 20, a small by-pass passage 52 is provided, as shown in Figure 1, between valve chamber 15 and gas passage 84. In order to control the gas flow through passage 52, a tapered needle valve 53 is 55 mounted in the bore 54 in valve body 11, with the tip projecting into the passage 52. Needle valve 53 is preferably fitted with a spring 55 and a soft packing ring 56 between the two metal washers 57 60 to prevent excessive gas leakage during adjustment. Bore 54 is preferably sealed off by a threaded plug 58 and a gasket 59.

Referring now to Figures 1, 5 and 6, the temperature control thermostat 49 of the embodiment illustrated utilizes two bimetallic spirals 60 secured to two slotted spindles 61, which are rotatably mounted between two plates 62 and 63. The thermostat 49 is symmetrical about its longitudinal center line, and, in Figure 5, the left 70 portion of upper plate 62 has been broken away to illustrate more clearly the connection between the valve stem 43 and the thermostat spirals 60. Figure 6 shows a section through one spiral 60 and 75 illustrates in detail its construction and the

method of adjustment to center the pivot points described below.

The center tongue or end 64 of each bimetallic spiral 60 is retained in the slot 65 of its corresponding spindle 61 as shown in Figure 6. The outermost end of each spiral 60 is provided with one or two recessed cups 66 into which the hardened steel pivot points 67 of the connecting link 68 are received. In the example shown in Figure 5 the right hand spiral has one recess, and the left hand spiral two recesses for a corresponding number of pivots on link 68.

Connecting link 68 is formed as shown in Figures 1 and 5 with two forks 69 and 70, fork 69 being the smaller and nearer the pivots 67 and 70 being the lower and longer. Fork 69 is adapted to closely contact the crank section 50 of the temperature control valve stem 43. Movement of the bimetallic spirals 60 due to ambient temperature change will be communicated to link 68, causing it to rotate about a center between the pivots 67. This causes an increased movement of the upper fork 69, which in turn moves crank 50 of valve stem 43 to open or close valve 44 and gas passage 38 leading to the burner 20. The lower fork 70 is adapted to straddle the lower bearing 51, with a limited clearance as shown, and acts as a limit stop to prevent too much motion of the link 68 and crank 50. Link 68 is therefore a floating connection between the bimetallic elements 60, whose efforts are cumulative, and valve stem 43. Normal side thrusts are substantially balanced, and have no appreciable effect upon the valve stem 43, which is only actuated by motions of the cups 66 on the spirals 60 substantially parallel to link 68.

Bimetallic spirals 60 are arranged with the metal having the higher expansion coefficient on the inside so that an increase in ambient temperature will cause the spirals to unwind. This will cause the outer ends and cups 66 to move counter-clockwise with respect to spindles 61. This movement of cups 66 will cause the link 68 to turn in a clockwise direction about the center 45 between the opposed pivots 67, and the fork 69 will move crank 50 of valve stem 43 to decrease or shut off the gas to burner 20. A decrease in ambient temperature will obviously have the opposite effect, and increase the gas flow.

It is quite obvious that other forms of temperature responsive devices could be substituted for thermostat 49 and particularly bimetallic elements 60, but the example shown has proved quite practical in actual tests of the device.

The initial pivot adjusting device and also the temperature setting adjustment mechanism is shown in detail in Figures 1, 5 and 6. In order to center the cups 66 on spirals 60 so that the pivots 67 will be in proper alignment, each slotted spindle 61, and therefore the spiral 60 is connected to its temperature adjusting lever 71 through the medium of a superimposed auxiliary lever 72. The bore or lever 72 through which spindle 61 passes is fitted with a tongue 13 which engages the slot 65 in spindle 61. The outer end of auxiliary lever 72 is adapted to be clamped to temperature adjusting lever 71 by a screw 14 which passes through a transverse slot 75 in lever 71. A nut 76 retains the auxiliary and temperature adjusting levers 72 and 71, the spacing washer 77, and the bimetallic spiral 60 on the spindle 61, the spiral being prevented from slipping off the lower end by the tongue 64 seating in the bottom of slot 65.

The position of bimetallic spirals 60 with re-

spect to pivots 67 obviously governs the temperature at which they will cause the temperature control valve stems 43 to open and shut the burner valve 44. This is controlled by the temperature adjusting levers 71 through the medium of the control lever 18. Lever 18 is pivoted on rivet 19 and has a downwardly depending arm 80 which engages both the levers 71 as shown in Figures 1 and 5. The outer ends of both levers 71 are urged together and held in contact with arm 80 by a tension spring 81. Inasmuch as both spirals 60 are wound in the same direction, the two adjusting levers 71 must also be moved in the same direction, which is accomplished by the arrangement shown. A 15 suitably calibrated scale 82 on the top of plate 62 may be provided, as well as limit stops 83 at the end of the scale.

In operation, to light burner 20, and assuming gas by-pass 52 to be open to a point which will allow a required minimum gas flow, the handle 21 of the safety shut-off valve stem 26 is moved in a clockwise direction, which withdraws the end 25 of the valve stem from hole 24 in safety shut-off thermostat element 22, and also opens 25 the safety shut-off valve 35. This permits gas from the supply tank (not shown) to flow from inlet chamber 14 through passage 33 into valve chamber 15, thence through by-pass 52 into passage 38 and to burner nozzle 40. This gas then 30 may be ignited by any suitable means, such as a lighted match, at the top of burner 20. In a few seconds the safety shut-off thermostat 22 will have expanded to its latched position (not shown) against the tube of burner 20. The handle 21 of shut-off valve stem 26 may then be released, and tip 25 will not be able to reenter hole 24 in element 22 because of the displacement due to the latter's expansion.

Should the ambient temperature to which the 40 temperature control thermostat 49 is exposed be below that at which the temperature control lever 18 is adjusted, that thermostat will have opened valve 44, which will admit a large flow of gas through passage 38 into burner nozzle 40 45 and it will burn at the top of burner 20. When the ambient temperature has risen a few degrees above the minimum desired, thermostat 49 will tend to close valve 44 and thereby reduce the rate of gas consumed. In actual practice, this 50 temperature differential has been found to be approximately 3 degrees Fahrenheit, which is well within the tolerance specified for refrigerator cars carrying perishable fruit and the like.

In case of accidental extinguishing of the high 55 or the low flame at the top of burner 20, the safety shut-off valve will function in the manner previously described to cut off all gas from valve chamber 15, so that no gas can be released to the burner 20 and to the atmosphere either 60 through the by-pass 52 or gas passage 38 to cause a fire or other hazard.

Although a specific construction embodying this invention has been described and illustrated, it is to be understood that the invention is not limited to that arrangement, and all such modifications and changes as come within the scope of the following claims are embraced thereby.

We claim:

1. In combination with a gas appliance having a burner therein, a casing, a gas passage in said casing communicating with said burner, a valve for said passage, a stem for said valve, a crank in said stem, opposed bimetallic elements 75

adjacent said casing and responsive to ambient temperature, a floating link cumulatively actuated by said elements, said link cooperating with said valve stem crank to open said valve upon a decrease in ambient temperature and close said valve upon an increase in ambient temperature.

5. 2. In combination with a gas appliance having a burner therein, a casing, a gas passage in said casing communicating with said burner, a valve for said passage, a stem for said valve, op-

posed bimetallic elements adjacent said casing and responsive to ambient temperature, a floating link cumulatively actuated by said elements, said link moving said valve stem to open said valve upon a decrease in ambient temperature and close said valve upon an increase in ambient temperature.

JOHN R. MACGREGOR.
LEON T. FOLSOM.
